LIQUID-DISPENSING MACHINE

Application filed August 1, 1925. Serial No. 47,428.

This invention relates to vending or dispensing machines, and relates more particularly to coin controlled machines for dispensing liquids and the like; and has special reference to the provision of a perfume vending machine of the atomizer type.

The prime consideratum of my present invention comprehends the provision of an improved vending machine for dispensing liquid materials such as perfume constructed and designed to meet the requirements of efficient operation and long service.

The principal objects of my present invention include more particularly the provision of a liquid vending machine embodying an atomizer dispensing device and a coin controlled pneumatic means for operating the same having a construction such that a predetermined and full measure charge of perfume spray may be dispensed at each operation of the machine and only when a coin of proper denomination is deposited therein; the further provision of an improved pneumatic operating means designed to be positive and reliable in action, simple in construction and durable in use, so as to require a minimum of attention for extended periods of service; the further provision of a machine of this nature in which the operations may be recorded or registered in a facile and reliable way; and the still further provision of an improved atomizer dispensing device constructed so as to prevent unauthorized siphoning of the machine and adjustable so as to regulate the liquid charge or spray delivered by the machine.

To the accomplishment of the foregoing and such other objects as will hereinafter appear, my invention consists in the elements and their relation one to the other, as herein-after particularly described and sought to be defined in the claims; reference being had to the accompanying drawing which shows the preferred embodiment of my invention, and in which:

Fig. 1 is a front elevational view of the dispensing machine with a part broken away;

Fig. 2 is an enlarged top plan view thereof with the cover removed, with parts broken away;

Fig. 3 is a view thereof taken in cross-section on the line 3—3, Fig. 2;

Fig. 4 is a view of the same taken in cross-section on the broken line 4—4, Fig. 3;

Fig. 5 is a cross-sectional view of parts of the atomizer dispensing device shown on an enlarged scale, 55

Fig. 6 is a view taken in cross-section on the line 6—6, Fig. 2, and

Fig. 7 is a view of a detail taken in cross-section on the line 7—7, Fig. 3. 60

Referring now more in detail to the drawings, the perfume dispensing machine of my present invention comprises a pneumatic actuating means generally designated as A adapted to be operated by means of a manually operable member generally designated as B when a coin of proper denomination is deposited into the machine, for operating the atomizer dispensing device, generally designated as C, to discharge therefrom a predetermined spray of liquid perfume, all supported by and housed within a cabinet generally designated as D. 65 70

The cabinet D comprises a housing or casing preferably made of sheet material having the front and rear walls 10 and 11, the side walls 12 and 13, and the bottom wall 14 attached together in any approved manner, and a removable top wall 15 having the downturned edge flanges 15' engaging the contiguous edge portions of the front and side walls 10, 12 and 13. The front wall 10 is provided with an opening 16 through which projects a delivery or discharge nozzle 17, said nozzle 75 being held in fixed relation on said front wall by means of the strap or yoke-shaped member 18 interiorly affixed to said wall. The front wall 10 is also provided with a removable closure 19 having the locking means 20, and which is removed when access to the interior of the casing is desired. The rear wall 11 of the casing has an upwardly extending section 11' which may be suitably ornamented as by 80 the provision of a reflecting device 21. The top wall 15 of the cabinet casing is provided with a coin chute 22 having a coin-receiving opening 23 and a curved coin slot or guide 24 85 projecting downwardly a distance below the 100

top wall 15 for a purpose which will become clearer hereinafter.

The pneumatic actuating means A comprises a pump cylinder 25 including a cylindrical wall 25¹ and the threadedly attached end walls 25² and 25³, the latter having a discharge nipple 25⁴, in which pump cylinder is movable a piston 26 fixed to an operating member in the form of a hollow piston rod 10 27 guided for reciprocable movement in the cylinder end wall 25². To the forward end of the piston rod 27 is fixed a coin receiving block 28 having a coin-receiving pocket 29 open at the top and bottom of the block, which 15 pocket is adapted to register with the coin chute or slot 24 when the reciprocable member or piston rod 27 is moved to its fully retracted position, as shown in Figs. 2, 3 and 4 of the drawings.

20 The manually operable member B comprises in its most simple form a rod 30 having an operating handle or knob 31 guided for slidable or reciprocable movement in a headed bushing 32 fixed to the front wall 10 of 25 the casing as by means of a nut 33 threaded onto the shank portion of the bushing, as clearly shown in Fig. 3 of the drawings, the said manually operable rod 30 being arranged for telescopic movement within the 30 hollow piston rod 27 in the absence of a coin in the block 28, and being arranged for operative connection to the piston rod 27 in the presence and through the medium of a coin such as 34 in said block. By means of this 35 construction, it will be apparent that a direct driving thrust is provided between the operating piston rod 27 and the manually operable member 30 through the medium of a coin, and that in the absence of a coin, the 40 rod 30 will slide telescopically within the piston rod for the full stroke thereof without operating the pneumatic means.

45 For positively withdrawing or retracting the piston rod 27 and the block 28 upon withdrawal or retracting movement of the manually operable rod 30, the rod 30 is provided with a pin or finger 35 arranged to engage a cross piece 36 integral with the coin block 28 (see Fig. 3), the bottom wall of the piston 50 rod 27 being longitudinally slotted as at 37 to permit relative and telescopic movement between the rods in the absence of a coin in the block, as will be readily understood.

55 By means of this construction, it will further be apparent that before the machine can be operated, the manually operable means B must be moved to a fully retracted position, such movement effecting the registering of the coin receiving block 28 with the 60 coin chute 22, and assuring a full operating stroke and hence a predetermined liquid discharge at each operation of the machine.

65 For the purpose of permitting the depositing of a coin into the chute 22 when the operable means B is in a non-retracted posi-

tion, the coin chute, the rod 30 and the block 28 are so coordinated that the rod 30 forms a stop and retaining means for the deposited coin when the rod is in a non-retracted position, the arrangement being such that when 70 the rod is moved to the fully retracted position, the coin drops into the block 28. To accomplish these objects, the lower end 24' of the coin slot 24 is spaced above the top wall of the operating rod 30 with a slight clearance such that the top wall of the rod 30 forms a stop or retaining means for the coin when the rod is in a non-retracted position, and the top wall of the rod 30 is flush with the inclined walls 38 of the block 28 (see 80 Fig. 2), the said walls communicating with the coin receiving pocket 29 of the block, as clearly shown in Figs. 2 and 3 of the drawings; the construction being such that as the rod 30 is moved outwardly, the coin rides 85 on the top wall of the rod and then drops or gravitates into the coin block as shown in Fig. 3 of the drawings.

An important feature of the invention resides in the provision of the simplified mechanism for accomplishing the functions and results already described, such as the operation of the pneumatic means only in the presence of a coin, the retracting movement of the pneumatic means to an initial position 90 for assuring the delivering or dispensing of a full charge of liquid material, and the preventing of the depositing of a coin until the parts are moved to the "start" or initial positions, the simplified mechanism for accomplishing these results consisting merely in the provision of a pair of relatively movable members such as the piston rod 27 and the operable rod 30. By simplifying the parts in this manner, I am enabled to provide a 95 positively acting and reliable machine not only, but one which is durable, and in which derangement of parts and hence replacement and repair is reduced to a minimum.

100 For inhibiting the operation of the machine with spurious coins, I provide a coin selecting means which preferably comprises a pair of elongated coin stop elements 39 and 40 arranged below the rods 27 and 30 105 spaced to define an opening 41 in registry with the bottom opening of the coin pocket 29, the spacing of the coin stop elements being such that a coin of proper denomination will be held by the stop elements in the coin block in position for engagement by the 110 manually operable rod 30, as clearly shown in Figs. 3 and 4 of the drawings, and such that a spurious coin will drop through the opening defined by the stop elements. In the preferred construction, each of the stop 115 elements comprises a member made of sheet material having a horizontal wall section 42 secured to a bottom plate 43, which latter is carried by the walls of the cabinet, a vertical 120 upstanding wall section 44, and an inturned 125

flange section 45, the inner edge of which provides the stop or retaining means for the coin. Preferably the stop elements 39 and 40 are relatively adjusted so as to vary or adjust the clearance or opening therebetween, and to this end the horizontal wall section 42 of the stop element 39 is provided with screw and slot adjusting means 46, 46, as clearly shown in Figs. 2 and 4 of the drawings.

10 In the preferred construction the coin selecting means 39, 40 is constructed to define a support and guide means for the operating parts of the machine, and to this end the flange elements 45, 45 also serve as a pair of guides which are received in guideways 47 provided in the coin receiving block 28; the construction being such that the block and the piston rod attached thereto are supported and guided for reciprocating movement in 15 the stop element guides.

For registering or counting the number of operations of the machine, there is provided a registering or counting device 48 hung on the plate 43, the said registering means including an operating arm or element 49 adapted to be actuated during each operation of the machine, the registering device being of the type wherein the arm 49 is returned to an initial or starting position after being 20 operated. To assure that that the registering device will be operated only when a coin is in the coin block, and to permit a return of the operating arm 49 to its initial position without interference from the movable or 25 operable parts of the machine, the operating arm 49 is arranged so as to project in the path of movement of the coin 34, the arm being directly engaged by the coin when the manually operable means B is moved forwardly as will clearly be apparent from a consideration of Figs. 3 and 4 of the drawings.

To prevent the return movement of the operating parts of the machine until after a complete or full stroke has been effected, 30 there is provided a pair of pawls 50, 50 pivotally mounted on opposite sides of the block 28, said pawls cooperating with a pair of ratchets 51, 51 fixed to the guide-stop elements 39 and 40. The inturned flange portions 45 of the guide-stop elements 39 and 40 are provided with the cut-aways 52, 52 at their inner ends, so as to permit the coin 34 to drop through the bottom opening of the coin block 28 when a full operating stroke of the 35 machine is completed, the said coin dropping into a coin box 53 arranged beneath the opening defined by the cut-away portions 52. By the provision of this construction, it will be apparent that the pawls 50 and ratchets 51 40 cooperate to prevent a return movement of the operating parts of the machine except after the operating stroke is completed, when the coin drops from the pocket 28; and hence undesirable repeated pumping action is inhibited.

The coin box 53 is preferably arranged in a separate compartment so that access thereto can be gained only by an authorized person, and to this end there is provided a vertical partition 54 spaced from the casing wall 13 and providing therewith a compartment open at its front end, which ends is provided with a removable closure 55 removably pivoted on the pivots 56 and provided with a lock 57, the bolt of which co-operates with a slotted member 58 fixed to the bottom wall 14 of the cabinet casing. For locking the top wall 15 in position, I provide a bolt rod 59 having a head 60 secured to the underneath wall of the top wall 15, the said bolt rod being received by a bayonet slot 61 provided in the plate 43 and being threaded at its lower end for reception of the wing nut 62, the said wing nut being adapted to be screwed against the underneath wall of the plate 43 for firmly locking the top wall or closure 15 in position, as will be apparent. With this construction access must first be gained to the interior of the casing before removal of the top closure can be effected.

The improved liquid dispensing means C of my invention comprises a liquid container 63 removably affixed to a strap or saddle 64 and connected to the nozzle 17 and to the pneumatic operating means A by means which may be regulated to effect the discharge of a predetermined quantity of liquid. This means comprises a cap or closure 65 for the container having a duct 66 communicating at one end with a pneumatic duct or pipe 67 connected to the nipple 25⁴ of the pump cylinder 25 and communicating at the other end with a branch pneumatic duct 68 having a part 68¹ extending into the container 63 and a part 68² extending from the liquid container to the nozzle 17 and provided with a port 69 opening into the nozzle 17. Arranged interiorly of the branch pneumatic duct 68 is a liquid discharge duct 70 extending from the liquid container 63 to the port 69, the liquid duct 70 terminating short of the said port 69, as is clearly shown in Fig. 5 of the drawings. By means of this construction the siphoning of the liquid container from an exterior point, such as from the nozzle 17, is prevented. For regulating the amount of liquid deliverable through the nozzle, I provide an adjusting screw 71 threaded in the branch pneumatic duct 68¹ and arranged to engage a flexible portion of the liquid discharge duct 68, the adjustment of the screw 71 predetermined the amount of liquid deliverable through the liquid discharge duct. This construction therefore permits the accurate regulation of the discharge spray, and prevents unauthorized siphoning of the liquid material from the perfume container.

The operation of my improved perfume dispensing machine and the many advantages thereof will in the main be apparent

from the above detailed description thereof. To operate the machine, the manually operable means B is moved to its outermost position as shown in Fig. 3 of the drawings, such movement effecting the retraction of the operating parts of the pneumatic means A. A coin deposited in the chute 22 then drops into the pocket 29 of the block 28 which now registers with the chute slot 24. If the coin 10 is of improper denomination, it will drop through the block, and if of proper denomination, will be held by the stop elements or retaining means 39 and 40 in the position as shown in Figs. 3 and 4 of the drawings, so as to form a medium connecting the pneumatic means A with the manually operable means B, so that pressure applied to the handle 31 of the latter will actuate the pneumatic means A and the atomizer device C to deliver 20 a full stroke charge of perfume through the delivery nozzle 17. The operation will be recorded on the registering device 48 which is actuated directly by the coin 34, the registering device being therefore operated only 25 when a coin is in the block, and being capable of unimpeded return movement. The parts may be readily regulated to serve for coins of different sizes by adjusting the coin stop element 39. In the absence of a coin in the 30 block, the means B may be manipulated by the operator without effect other than to retract the parts of the pneumatic operating means to the initial or "starting" position. If the operating parts are not in the "starting" position, a coin deposited in the chute will not be delivered to the coin pocket 29, but will be held in the chute by the rod 30 until the latter is withdrawn to its outermost position, at which time the coin will fall into 35 said pocket. The atomizer functions to positively deliver a charge of perfume, the amount of which may be predetermined by adjustment, the parts of the atomizer furthermore being constructed to prevent any 40 unwarranted siphoning of the perfume by an unauthorized person.

These and the other coordinated functions previously referred to are thus accomplished by the provision of mechanism having few 45 parts relatively arranged in accordance with an exceedingly simple law of organization and cooperating in a simple way to effect a positive operation of the machine for producing a sure delivery of the liquid perfume in 50 a predetermined amount. The parts are capable of rugged design, and this combined with the simplicity of organization of the parts results in the production of a machine which is strong, durable and subject to a 55 minimum amount of derangement, even after 60 long periods of service.

While I have shown and described my invention in the preferred embodiment, it will be apparent that numerous changes and modifications may be made in the structure dis-

closed without departing from the spirit of the invention defined in the following claims.

I claim:

1. In a vending machine for dispensing liquids, a pneumatic actuating means including a hollow reciprocable operating member, a coin receiving block fixed to the forward end of said member, a manually operable rod arranged for telescopic movement within said hollow member in the absence of a coin in said block and for operative connection to said member in the presence and through the medium of a coin in said block, complemental means on said rod and member for permitting the relative and telescopic movement between the rod and member upon the forward movement of the rod and for effecting the retracting movement of the member upon retracting movement of the rod, and a coin chute arranged to register with the coin block when said member is in its fully retracted position, the lower end of the coin chute being disposed relatively to said rod so that the rod forms a stop for a deposited coin when the rod is in a non-retracted position and the rod being arranged for communication with the coin receiving block so that the coin rides on the rod and drops into the block as the rod is moved to its retracted position, and spaced guides extending from the bottom of the coin block to support a coin of proper size in front of the plunger and during active movement thereof, the guides being interrupted at their inward ends to permit downward discharge of the coin upon retraction of the plunger. 70 80 90 95 100

2. In a vending machine for dispensing liquids, an actuating means including a reciprocable operating member, a manually operable member, a coin receiving block on one of said members, the manually operable member being arranged for telescopic movement relative to the operating member in the absence of a coin in said block and for operative connection to said operating member in the presence and through the medium of a coin in said block, complemental means on said members for permitting relative and telescopic movement between the members upon forward movement of the operable member and for effecting the retracting movement of the operating member upon retracting movement of the operable member, and a coin chute arranged to register with the coin block when the coin block is in its fully retracted position, the lower end of the coin chute being spaced above the top wall of the operable member so that the latter forms a stop for a deposited coin when the members are in non-retracted position, the top wall of said operable member communicating with the coin block so that the coin rides on said operable member and then drops into the coin block as said member is moved to its retracted position, and spaced 110 115 120 125 130

guides extending from the bottom of the coin block to support a coin of proper size in front of the plunger and during active movement thereof, the guides being interrupted at their inward ends to permit downward discharge of the coin upon retraction of the plunger.

3. In a vending machine, an actuating means including a reciprocable operating member, a manually operable member, a coin receiving block on one of said members, said coin receiving block having a coin pocket open at the top and bottom of the block, the manually operable member being arranged for telescopic movement relative to the operating member in the absence of a coin in said pocket and for operative connection to said operating member in the presence and through the medium of a coin in said pocket, and a coin selecting means arranged below said members and block having spaced elongated coin stop elements defining therebetween an opening in registry with the bottom opening of the coin pocket, the spacing of the coin stop elements being such that a coin of proper denomination will be held by the stop elements in the coin block in position for engagement by the manually operable member and a spurious coin will drop through the opening defined by the stop elements, the said stop elements also defining a support and guide means for the members and block and being cut away at their inner ends to permit a coin in said pocket to drop after a full stroke operation of the machine.

35 Signed at New York city, in the county of New York and State of New York this 30th day of July A. D. 1925.

FRED T. ROBERT.
